FIG. 4 28 William L. Stark

BY *Richard Oliver*

ATTORNEY

UNITED STATES PATENT OFFICE.

WILLIAM L. STARK, OF HASTINGS, MICHIGAN.

WASHING-MACHINE.

1,217,656.

Specification of Letters Patent. Patented Feb. 27, 1917.

Application filed October 28, 1916. Serial No. 128,319.

To all whom it may concern:

Be it known that I, WILLIAM L. STARK, a citizen of the United States, residing at Hastings, in the county of Barry and State 5 of Michigan, have invented certain new and useful Improvements in Washing-Machines, of which the following is a specification.

This invention relates to an improved washing machine and the principal object 10 of the invention is to provide a washing machine having improved operating mechanism for the sliding board or frame mounted in the receptacle in which the clothes and water are placed and to further provide an im- 15 proved type of movable and substantially stationary type of rack between which the clothes will be pressed and turned during the washing operation.

Another object of the invention is to pro- 20 vide a washing machine having its actuating means so constructed as to include double levers, one being moved by the other and so constructed that they may be separated when so desired.

25 Another object of the invention is to so construct this actuating mechanism for the movable clothes engaging rack or frame that it may be very easily moved and the clothes tightly compressed between the two racks 30 with a minimum amount of labor.

Another object of the invention is to so construct this washer that it will comprise a comparatively few number of parts and to further so construct it that it will be strong 35 and durable and not liable to easily get out of order or break.

This invention is illustrated in the accom- 40 panying drawings, wherein:—

Figure 1 is a view showing the improved 45 washer in side elevation,

Fig. 2 is a vertical transverse sectional view taken along the line 2—2 of Fig. 1.

Fig. 3 is a longitudinal sectional view 50 through the improved washer.

Fig. 4 is a top plan view of the washer 55 with the cover removed.

This washer is provided with a water receptacle or body 10 which is supported by the legs 11 and is provided with a cover in- 60 cluding the two sections 12 and 12' hingedly connected as shown at 13. Within the receptacle there is provided the substantially stationary clothes engaging rack 14 having the cross ribs 15 and hingedly mounted at its 65 lower end as shown at 16 and yieldably held

in the extended position shown in Fig. 3 by means of the springs 17.

Within this receptacle there is provided the movable clothes engaging rack indicated in general by the numeral 18 and pro- 60 vided with the cross ribs 19 similar to the cross ribs 14 spaced as shown so that water may pass through the rack. A rocker shaft 20 is rotatably mounted to extend through the receptacle 10 and carries arms 21 piv- 65 otally connected with the links 22 which in their turn are connected with the movable rack 18 so that as the rocker shaft is rotated, the movable rack or frame will be reciprocated in the receptacle. A yoke or 70 main handle indicated in general by the numeral 23 is provided with side arms 24 which have their lower ends engaged by the yoke or clamping bracket 25 pivotally connected with the standards or bearing brackets 26 75 secured to the upper end portions of the supporting legs 11 at one end of the receptacle. This main handle or yoke extends between the cross rods 27 of the auxiliary handle which has its side arms 28 connected with 80 the outer ends of the rocker shaft 20 and it will thus be seen that when the main handle is moved, the auxiliary handle will also be moved and the rocker shaft rotated first in one direction and then in the other thus 85 causing the movable clothes engaging rack or frame 18 to reciprocate longitudinally in the receptacle. Therefore when the main handle is swung downwardly, the movable clothes engaging rack will be moved toward 90 the substantially stationary clothes engag- 95 ing rack and the clothes placed in the wash- ing machine between these two racks will be pressed into tight engagement with the stationary rack and the stationary rack 95 moved toward the end of the washing ma- chine. It should be noted that as the main handle is swung downwardly and the auxiliary handle swung to rotate the rocker shaft, the auxiliary handle will move closer to the 100 inner ends of the side bars of the main han- dle and therefore the leverage will be in- creased and the pressure applied to the clothes between the racks increased thus squeezing the clothes very tightly and forc- 105 ing the water out of them. It will thus be seen that the greatest amount of pressure will be applied when needed for expelling the water from the clothes in the receptacle.

When the main lever is swung upwardly, 110

the pressure will be removed from the clothes and the substantially stationary rack will be moved to its original position by the springs 17 thus partially turning the 5 clothes in the receptacle. Upon the main handle being again swung downwardly, the clothes will be again compressed and of course the water squeezed out of them. It will thus be seen that the water will be 10 forced through the clothes and thus the clothes easily and quickly cleaned. The cover may be open from either end or may be entirely removed if so desired. If it is desired to open the receptacle from the end 15 with which the main and auxiliary handles are connected, the auxiliary handle will be swung upwardly so that it will pass out of engagement with the main handle and can then be turned to extend in the opposite direction from that shown in Fig. 1. If desirable or necessary the main handle can be released from engagement by the clamps or sockets 25 thus making it easier to disconnect the two handles. I have thus provided a 20 washing machine which will be very easy to handle, since the cover can be entirely removed and the clothes and water then placed in the machine and have further provided a washing machine so constructed that 25 the operating mechanism for the movable clothes engaging rack will be very easy to move and have a great deal of power.

What is claimed is:—

1. A washing machine comprising a 35 receptacle, clothes pounding means in said receptacle, and actuating means for said clothes pounding means comprising a rocker shaft extending through the receptacle, an auxiliary handle including side bars con-

nected with the outer end portions of the 40 rocker shaft and cross rods connecting the side bars, sockets pivotally connected with said receptacle, and a main handle extending between the cross rods of the auxiliary 45 handle and including side bars extending into said sockets and engaging the cross rods of the auxiliary handles whereby rocking of the main handle will swing the auxiliary handles to rotate the rocker shaft and move the auxiliary handle longitudinally upon the 50 main handle.

2. A washing machine comprising a receptacle, clothes pounding means slidably mounted in said receptacle, a rocker shaft extending through the receptacle, arms 55 extending from the rocker shaft, links connecting the arms with the clothes pounding means for imparting sliding movement to the same as the rocker shaft rotates, a main handle including side bars pivotally connected with the receptacle and a cross bar connecting side bars, and an auxiliary handle including side bars connected with the outer end portions of the rocker shaft, and 60 cross rods connecting side bars of the auxiliary handle, the main handle extending between the cross bars of the auxiliary handle for swinging the auxiliary handle to rotate the rocker shaft and moving the auxiliary handle longitudinally upon the main 65 handle as the main handle is moved.

In testimony whereof I affix my signature in presence of two witnesses.

WILLIAM L. STARK.
